UNITED STATES PATENT OFFICE.

JOHN W. THOMAS, OF AMARILLO, TEXAS.

FROG AND GUARD RAIL FOR RAILWAY-TRACKS.

994,215.

Specification of Letters Patent. Patented June 6, 1911.

Application filed September 17, 1910. Serial No. 582,568.

To all whom it may concern:

Be it known that I, JOHN W. THOMAS, a citizen of the United States, residing at Amarillo, in the county of Potter and State of Texas, have invented certain new and useful Improvements in Frog and Guard Rails for Railway-Tracks, of which the following is a specification.

My invention relates to improvements in 10 frog-and-guard-rails for railway-tracks, and my object is to provide a simple device of this character containing certain features of advantage hereinafter described.

In order that the invention may be fully 15 understood reference will now be made to the accompanying drawing in which:

Figure 1 is a plan view partly in section of the invention in operative position. Fig. 2, is a detail plan view of one of my frog-and-guard-rails. Fig. 3, is a plan view of 20 one of my frog and guard rails applied to a spring-frog.

1 and 2 designate main-line rails, and 3 and 4 designate branch-line rails.

25 5 designates the frog-point.

6 and 7 designate wing-rails communicating with rails 2 and 3, respectively, and located at opposite sides of the frog-point 5, to which they are secured by bolts 8, 30 fillers 9 being interposed between said wing-rails and the frog-point to leave space for the passage of flanges on the wheels of passing trains.

10 and 11 designate guard-rails located 35 adjacent rails 1 and 4, respectively. Guard-rails 10 and 11 have segmental terminals 12 and 13, and semicircular ends 14 and 15 which latter have extensions 16 and 17 secured, respectively, against wing-rails 3 and 40 2 by bolts 18, fillers 19 being interposed between said extensions and the wing-rails, as shown in Fig. 1. Terminals 12 and 13 abut against the out-turned ends 20 and 21 of the wing-rails 3 and 2, respectively, to which 45 they are removably secured by plates 22 and bolts 23.

24 and 25 designate fillers interposed between frog-guard-rails 10 and 11 and rails 1 and 4 respectively, which are secured together by bolts 26 extending through the 50 fillers.

By curving the ends of the guard-rails and having them engage the wing-rails and the line-rails, it is obvious that said rails will be reliably held in place and secured 55 from spreading apart or moving toward each other, and by reinforcing the wing-rails with extensions 16 and 17, said wing-rails are protected from wearing and being broken by the car-wheels passing over the 60 same, the extensions, in this respect, forming important features of the invention.

When my improved frog and guard rails applied to a spring-frog, as shown in Fig. 3, one of my improved rails is dispensed 65 with to permit action of the spring-controlled wing-rail 2^a during the passage of a train.

Having thus described my invention what 70 I claim is:

1. In combination with the line and wing rails of a frog, a frog-and-guard-rail curved at each end and provided with an extension adapted to lie against one of the wing rails, and means for securing said frog-and-guard- 75 rail to the line-and-wing-rails.

2. In combination with the line and wing rails of a frog, frog-and-guard-rails each curved at its ends and provided with an extension adapted to lie against a wing-rail, 80 each of said frog-and-guard-rails also having a portion paralleling one of the line rails, substantially as described.

In testimony whereof I affix my signature, in the presence of two witnesses.

JOHN W. THOMAS.

Witnesses:

F. G. FISCHER,
E. C. LILLIAN.
